UNITED STATES PATENT OFFICE.

JAMES ROSSITER HOYLE AND ARTHUR WILLIAM BREARLEY, OF SHEFFIELD,
ENGLAND, ASSIGNORS TO THOMAS FIRTH AND SONS LIMITED, OF SHEFFIELD,
ENGLAND.

CASTING INGOTS.

1,073,988.

Specification of Letters Patent. Patented Sept. 23, 1913.

Application filed December 13, 1912. Serial No. 736,582.

To all whom it may concern:

Be it known that we, JAMES ROSSITER HOYLE and ARTHUR WILLIAM BREARLEY, subjects of the King of England, and both 5 residing at Sheffield, Yorkshire, England, have invented certain new and useful Improvements in Casting Ingots, of which the following is a specification.

This invention relates to the casting of 10 ingots through the bottom of the mold, particularly groups of ingots, and has for its object to prevent the formation of shrinkage cavity or pipe in the ingots.

According to this invention the formation 15 of pipe or cavity within the ingot is prevented by means of a nozzle or short sleeve placed in the base of the mold and forming a continuation of the runner brick, the nozzle being automatically heated to incandescence by the incoming metal as it rises 20 through the base of the mold. As soon as the mold is filled it is reversed, so that the hottest metal, which occupies the widest part of the mold, is brought to the top of 25 the ingot where it is maintained in a molten state by the nozzle which has been automatically heated in the manner described.

The reversed position of the mold (not 30 shown in the drawings) will bring its wide end uppermost so that not only does the ingot solidify in a conical mold having its wide end uppermost, but in addition the nozzle, thus automatically heated, causes the metal in the upper part of the mold to feed 35 downward into any shrinkage cavity in the lower part of the ingot, thus preventing the formation of any cavity or pipe within the ingot, as the molten metal in contact with the incandescent nozzle cannot solidify 40 and therefore sinks with a level surface and forms no appreciable pipe.

The invention is particularly applicable 45 to the casting of ingots in groups, and in such cases all the molds are mounted on a casting plate which, after the molds have been filled, is turned over so as to invert all the molds simultaneously.

In the accompanying drawings which 50 show one form of apparatus for bottom casting ingots in groups in accordance with this invention, Figure 1 is an end elevation partly in section. Fig. 2 is a plan. Fig. 3 is a sectional side elevation through the molds and casting plate. Fig. 4 shows in 55 plan on an enlarged scale a modified form of

firebrick plate for the base of the mold, and Fig. 5 is a section on the line 5—5 of Fig. 4, showing a portion of the nozzle and runner brick.

In the construction illustrated the apparatus 60 comprises a casting plate A provided with trunnions A' mounted in standards B disposed on either side of a pit C. The casting plate carries the trumpet pipe D which communicates by means of runner 65 brick conduits E with the base of each of the molds F, six of which are shown in the construction illustrated. The molds are secured in place on the casting plate A by means of T-bolts and cotters G, G'. A circular hole E' is formed in the runner brick central with each mold, and above each aperture E' is placed a perforated plate or disk of firebrick H', the aperture in which corresponds with the hole E'. Resting on 70 the plate H' so as to extend a short distance upward from the base of each mold, is a short sleeve or nozzle of firebrick H, the taper of the mold and nozzle maintaining the latter in place after the molds have 75 been inverted.

In the modified form of plate H³ shown in Figs. 4 and 5, in place of a single central aperture a series of inclined conduits H² are provided each of which communicates with 85 the opening E' in the runner brick E. The inclination of the conduits H² (four of which are shown in the example illustrated) is such that the molten metal as it rises through the plate is directed against the 90 walls of the nozzle H which is thus more efficiently heated than in the case of a single vertical aperture or conduit in the plate H'.

The molds are filled in the usual manner 95 through the trumpet pipe D, the open end of which is then covered with damp sand and closed by means of an iron plate or the like J held in place by a wedge J' which passes under a locking bar K mounted in lugs K' formed on the trumpet. At this 100 stage the entire casting plate A, together with the molds F secured thereto, is rotated about the trunnions A', by any suitable mechanism (not shown) so that the molds are inverted, and in this way the nozzles H 105 and plates H³ brought to the upper ends of the ingots.

When the molten metal is poured through the trumpet D it rises through the nozzles H into the conical molds F, and in so rising 110

2

heats the nozzles H and plates H^3 to incandescence, the inclined conduits H^2 , when such are employed, further assisting in the heating of the nozzles. When therefore the 5 molds are inverted in the manner above described, the most recently introduced metal is brought to the top of each mold so that each ingot solidifies in a conical mold having its wide end uppermost, the metal in the 10 widened upper end of the mold being maintained in a molten state by the heated nozzle which allows the metal to sink with a level surface and so prevents the formation of any appreciable cavity or pipe in the ingot.

15 What we claim as our invention and desire to secure by Letters Patent is:—

1. The method of preventing the formation of shrinkage cavity within bottom cast ingots which consists in introducing the 20 metal into the mold through a nozzle of refractory material placed in the base of the mold, heating said nozzle to incandescence by the incoming metal, and reversing the mold, said nozzle after the mold is reversed 25 causing the metal in contact therewith to feed downward into any shrinkage cavity within the ingot.

2. The method of preventing the formation of shrinkage cavity within ingots which 30 are bottom cast in groups which consists in securing a plurality of molds to a casting plate so as to communicate with the pouring trumpet, placing a refractory nozzle within the base of each mold and heating said nozzles to incandescence by the incoming metal, then reversing the casting plate and the molds mounted thereon, whereby the most 35 recently introduced metal is brought to the top of each mold where it is maintained at a high temperature by the heated nozzle for the purpose set forth.

40 3. The method of preventing shrinkage cavity in ingots which are bottom cast in groups, which consists in securing to a casting plate a plurality of taper molds which widen toward their bases, said molds com-

municating by runner brick conduits with the pouring trumpet, placing a nozzle and a perforated plate both of refractory material within the widened base of each mold 50 and heating said nozzles and plates to incandescence by the incoming metal, then closing the mouth of the trumpet and reversing the casting plate together with the molds mounted thereon whereby each ingot 55 solidifies wide end uppermost, and the most recently introduced metal is brought to the top of each mold where it is maintained at a high temperature by the heated nozzle so that the metal in contact therewith is 60 maintained in a molten state for the purpose described.

4. The method of preventing shrinkage cavity in ingots which are bottom cast in groups, which consists in securing to a casting plate a plurality of taper molds which widen toward their bases, said molds communicating by runner brick conduits with the pouring trumpet, placing a nozzle and a plate both of refractory material within the 65 widened base of each mold, said plate having a plurality of inclined conduits whereby the incoming metal is directed against the walls of the nozzle thus heating said walls to incandescence, then closing the mouth of the trumpet and reversing the casting plate together with the molds mounted thereon whereby each ingot solidifies wide end uppermost, and the most recently introduced metal is brought to the top of each mold 70 where it is maintained at a high temperature by the heated nozzle so that the metal in contact therewith is maintained in a molten state for the purpose described.

75 In testimony whereof we have signed our names to this specification in the presence of two subscribing witnesses.

JAMES ROSSITER HOYLE.
ARTHUR WILLIAM BREARLEY.
